UNITED STATES PATENT OFFICE.

EDWARD ERICKSON, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

OPERATOR'S CHAIR.

1,318,439.

Specification of Letters Patent. Patented Oct. 14, 1919.

Application filed June 18, 1917. Serial No. 175,423.

To all whom it may concern:

Be it known that I, EDWARD ERICKSON, a citizen of the United States, residing at Beverly, in the county of Essex and State 5 of Massachusetts, have invented certain Improvements in Operators' Chairs, of which the following description, in connection with the accompanying drawings, is a specification, like reference characters on the 10 drawings indicating like parts in the several figures.

This invention relates to chairs and particularly to improvements in chairs for the use of the operators of machines in factories.

15 An object of this invention is to improve chairs for the above purpose so that they will be more comfortable, convenient, durable and safe although inexpensive to manufacture.

20 With a view to increasing the safety of chairs for this purpose, one feature of the invention consists in improving the folding mechanism of chairs designed to leave the aisles clear when the chairs are unoccupied 25 so as to allow the operators to leave the room hurriedly in case of panic, fire or other accident.

With the object in mind of producing a comfortable and convenient chair, an important feature of the invention consists in 30 providing simple means for adjusting the height of the chair and in also providing means for permitting the chair to turn to a limited extent when the operator wishes to 35 occupy it or to rise therefrom while, at the same time, providing means for automatically locking the chair in position as soon as it receives the weight of the operator. Thus, the advantage of a swivel chair is secured 40 when the operator starts to occupy it or rises therefrom, while it also has the advantage that it will remain in fixed relation to the machine during the time that the operator is at work. Therefore the chair 45 can not move inadvertently and cause the operator to become injured or spoil the work. Furthermore, means are provided for adjusting the chair on the floor and then locking it in the position best suited to meet 50 the requirements of the operator.

With the object of durability in mind, the chair is made principally of metal in order to withstand the hard usage to which factory chairs are subjected.

Other features and objects of the invention will be apparent when the following description and claims are considered in connection with the accompanying drawings.

In the drawings: Figure 1 is a side elevation of the chair in folded position, dotted lines showing the chair in position for occupancy;

Fig. 2 is a rear elevation of the chair in folded position, and

Fig. 3 is a detail of the means for adjusting the height of the chair and providing for a limited turning thereof.

Referring to the drawings in detail: The base portion 6 of the chair consists 70

of a casting having an upwardly extending socket 10 to receive the upright which supports the chair, as will be described in detail later. In order to permit the position of the chair upon the floor to be adjusted, 75 a T-slot casting 4 is provided which is fastened to the floor by means of screws. Before this piece is secured to the floor, a screw is placed with its head located in the wide portion of the slot and with the threaded 80 portion extending upright to pass through a slot provided in the base portion 6, which slot is located substantially at right angles to the T-slot in the casting 4. A nut 8 on the screw fastens the base portion securely 85 against the floor after the chair has been located to meet the requirements of the operator. This construction increases the usefulness of the chair when combined with the other features of construction of the present invention.

In the socket 10 is slidably located the seat supporting upright 12. This is preferably made of tubing to economize in material and to lessen the weight. To this tube 95 is pivotally connected at 14 a spider frame 22 to which the seat 13 is secured. A coil spring 16, coaxial with the pivot 14, has its two straight ends 18 and 20 bear respectively against the inside of the upright 12 100 and against the under side of the seat 13. This spring causes the chair to assume the full line position of Fig. 1 when it is unoccupied but allows it to readily assume the dotted line position when the chair receives 105 the weight of the operator, as will be better understood after the chair has been more fully described.

To the spider frame 22 is pivotally connected a back-rest support holder 24 on which the back-rest support 28 is clamped in any desired adjusted position by means 5 of the binding screw 29 and clamp 30. The back-rest support 28 is composed of a unitary piece of tubing in the form of an inverted U and has a back-rest 31 secured at its upper end. The back-rest support holder 10 24 is connected with the upright by means of a brace 26. This brace 26 is pivotally connected to both the back-rest support holder 24 and the upright 12. Upon the brace is formed a lug 46 which bears against 15 the socket 10 when the chair is occupied. This lug supports the brace 26, which in turn supports the rear end of the seat through the back-rest support holder 24. It will thus be seen that the parts 22, 24 and 20 26 form a link-motion for allowing the chair to open or to fold up, the lengths of the links being so chosen that the part 24 maintains the back-rest support and the back-rest at substantially the same angle relatively to the floor in both positions. By 25 such a design the back-rest is folded close to the bench when the chair is unoccupied, leaving the aisle clear for the purpose above set forth.

30 A convenient and novel construction for adjusting the height of the seat, and at the same time for permitting limited angular movement of the seat so as to make it easy for the operator to occupy the chair or rise 35 therefrom, is shown in detail in Fig. 3 and consists of the loose sleeve 32 and the parts coöperating therewith. This sleeve loosely surrounds the upright 12 in the illustrated embodiment of the invention and is provided 40 at its upper end with three pairs of vertical notches 34, 36 and 38. The notches of each pair are diametrically opposite each other and are of equal depth but each pair is of different depth than that of the other 45 pairs. When the chair is lifted somewhat in the socket 10, the sleeve may be freely turned around upon the upright until the desired pair of notches is in position to engage the bolt 40 which pivotally connects the brace 26 and the upright 12. When the chair is 50 dropped back in its socket, the bolt 40 rests in the bottom of the pair of notches then engaged, the particular pair of notches with which it is engaged determining the height 55 of the chair. At the lower end of the sleeve 32 are a series of notches 42 which are of equal width, one pair of which will be engaged with the raised stops 44 upon the top of the socket 10, according to which pair of upper notches is engaged with the bolt 40. As the notches 42 are wider than the stops 44, a limited amount of angular movement is permitted between the notches and stops. This allows limited angular movement of the 60 chair, which movement is the same for each 65

of the adjusted positions of the sleeve 32, for the reason that the upper and lower notches of the sleeve are symmetrically located relatively to each other.

This sleeve 32 thus provides a very simple 70 and effective means for adjusting the height of the seat and permitting limited rotation thereof, no tools whatever being required to make the adjustment for height.

When it is desired to raise the chair to a 75 height greater than is permitted by the sleeve 32, a longer sleeve may conveniently be substituted therefor or the chair may be clamped in raised position, if the turning feature is not desired, by means of the bolt 80 48 which draws the socket together into clamping position, the socket being split at 50 to allow it to spring together.

Besides the function already mentioned, the lug 46 bears firmly against the socket 85 10 when the chair is occupied, so that the chair is clamped in the desired angular position. However, as soon as the operator starts to rise and the chair starts to fold up, the clamping action is released and the 90 chair may then be turned so that there will be plenty of space for the operator to rise.

Having thus described the invention, what is claimed as new and desired to be secured by Letters Patent of the United States 95 is:—

1. A folding chair, having, in combination, a base portion constructed and arranged to be secured to a floor, an upright mounted on said base portion, a seat pivotally connected to said upright, a back rest support holder, a back rest support secured to said holder, a back rest on said support and a brace pivotally connected to the upright, said holder being pivotally connected to the 100 seat and to the brace.

2. A folding chair, having, in combination, a base portion constructed and arranged to be secured to a floor, an upright mounted on said base portion, a seat pivotally connected to said upright, a back rest support holder, a back rest support secured to said holder, a back rest on said support, and a brace pivotally connected to the upright, 110 said holder being pivotally connected to the seat and to the brace, and said pivotally connected members forming a link-motion so constructed and arranged that the back rest support holder maintains the back rest support at substantially the same angle relatively to the floor in both the open and folded positions of the chair.

3. A folding chair, having, in combination, a base portion constructed and arranged to be secured to a floor, an upright mounted 125 on said base portion, a seat pivotally connected to said upright, a back rest support holder, a back rest support, a back rest on said support, and a brace pivotally connected to the upright, said holder being pivot- 130

ally connected to the seat and to the brace, and said pivotally connected members being constructed and arranged to cause the back rest support to rise and simultaneously to move forward toward the front of the chair when it is being folded.

4. A folding chair, having, in combination, a base portion constructed and arranged to be adjustably secured to a floor, an upright mounted on said base portion, a seat pivotally connected to said upright, a back rest support holder, a back rest support comprising a unitary member adjustably secured to said holder, a back rest on said support, a brace pivotally connected to the upright, said holder being pivotally connected to the seat and to the brace and a spring for causing the chair to fold up when the occupant rises therefrom.

5. An adjustable chair, having, in combination, a base portion constructed and arranged to be secured to a floor, an upright mounted on said base portion, a seat supported by said upright, stops on the base portion and the upright and a loose sleeve constructed and arranged to coöperate with the stops in any one of a plurality of different positions to adjust the height of the seat and permit limited rotation thereof.

6. An adjustable chair, having, in combination, a base portion constructed and arranged to be secured to a floor, an upright mounted on said base portion, a seat supported by said upright, one set of stops on the base portion and another set on the upright and a loose sleeve having in one end a plurality of notches of equal size to coöperate with one set of stops and having in the other end a plurality of pairs of notches to coöperate with the other set of stops, the notches of each pair being diametrically opposite each other and of equal depth but the notches of each pair being of different depth from those of the other pairs.

7. An adjustable chair, having, in combination, a base portion constructed and arranged to be secured to a floor, an upright mounted on said base portion, a seat supported by said upright, one set of stops on the base portion and another set on the upright and a loose sleeve having, in one end, a plurality of notches to engage one set of stops, said notches being wider than the stops to permit limited relative angular movement between the notches and stops, and said loose sleeve having, in the other end, a plurality of pairs of notches, each pair of a different depth, and any pair being adapted to be engaged selectively with the other set of stops to permit the height of the seat to be adjusted.

8. A folding chair, having, in combination, a base portion constructed and arranged to be secured to a floor, an upright mounted on said base portion, a seat pivotally con-

nected to said upright, a back rest support holder, a back rest support secured to said holder, a back rest on said support, a brace pivotally connected to the upright, said holder being pivotally connected to the seat and to the brace, means for causing the chair to fold up when the occupant arises therefrom, stops on the base portion and on the upright and a loose sleeve constructed and arranged to coöperate with the stops in any one of a plurality of different positions to adjust the height of the seat and permit limited rotation thereof.

9. A folding chair, having, in combination, a base portion constructed and arranged to be secured to a floor, an upright mounted on said base portion, a seat pivotally connected to said upright, a link member, a brace, a bolt pivotally connecting the brace and the upright, said link member being pivotally connected to the seat and to the brace, means for causing the chair to fold up when the occupant arises therefrom, a stop on the base portion and a loose sleeve having, in one end, a plurality of notches of equal size to coöperate with the stop and having, in the other end, a plurality of pairs of notches to engage with the pivot connecting the brace and the upright, the notches of each pair being diametrically opposite each other and of equal depth but the notches of each pair being of different depth from those of the other pairs.

10. A folding chair, having, in combination, a base portion constructed and arranged to be secured to a floor, an upright mounted on said base portion, a seat pivotally connected to said upright, a link member, a brace pivotally connected to the upright, said link member being pivotally connected to the seat and to the brace, means for permitting limited angular movement of the chair and means for maintaining the chair in fixed angular position when it is occupied.

11. A folding chair, having, in combination, a base portion constructed and arranged to be secured to a floor, an upright mounted on said base portion, a seat pivotally connected to said upright, a link member, a brace pivotally connected to the upright, said link member being pivotally connected to the seat and to the brace, a stop on the base portion, a loose sleeve having in one end a plurality of notches to engage the stop, said notches being wider than the stops to permit limited relative angular movement between the notches and stop, and a lug on the brace constructed and arranged to engage the base portion when the chair is occupied and maintain the chair against angular movement.

12. A mechanism for adjusting the height of a chair, having, in combination, a member connected to the chair, a member con-

nected to the floor, and means coöperating between them comprising a stop and a plurality of notches of different depths, any notch being adapted to be engaged selectively with said stop to permit the height of the chair to be adjusted.

13. A folding chair, having, in combination, a base portion constructed and arranged to be secured to a floor, an upright 5 mounted on said base portion, a seat pivot-

ally connected to said upright, a link member, a brace pivotally connected to the upright, said link member being pivotally connected to the seat and to the brace, and means for causing the chair to fold up when the occupant rises therefrom. 15

In testimony whereof I have signed my name to this specification.

EDWARD ERICKSON.
